UNITED STATES PATENT OFFICE.

JOHN LOFTUS, OF ALBANY, NEW YORK.

INTERNAL-COMBUSTION ENGINE.

1,058,992.

Specification of Letters Patent. Patented Apr. 15, 1913.

Application filed September 6, 1912. Serial No. 718,892.

To all whom it may concern:

Be it known that I, JOHN LOFTUS, a citizen of the United States, residing at Albany, in the county of Albany and State of New York, have invented certain new and useful Improvements in Internal-Combustion Engines, of which the following is a specification.

My invention relates to improvements in internal combustion engines, and more particularly to that class or type in which the power and compression cylinders and pistons are arranged in axial line with each other, the primary object being to provide a generally improved internal combustion or hydrocarbon engine of exceedingly simple, cheap, and efficient construction, the present embodiment being particularly designed and adapted for use in connection with volatile fuels or liquid hydrocarbons of low specific gravity, such as benzine, gasoline, naphtha, petrol, and the like, which volatilize readily on exposure to the atmosphere or on the application of heat.

Generally speaking, the invention consists in a power cylinder provided with a cylindrical abutment head extending into and spaced from its side walls forming an annular combustion chamber and a combined power and compression piston in the form of a trunk piston or shell, the latter operating over and in conjunction with said cylindrical abutment and within said annular combustion chamber and forming a compression chamber in front of said cylindrical abutment, said compression chamber within said trunk piston being adapted to coöperate with the adjacent parts and to be thrown into and out of communication with said annular combustion or power chamber.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings forming a part of this specification, Figure 1, is a central vertical sectional view of an engine constructed in accordance with my invention, the improved piston being shown at or near the end of its down stroke. Fig. 2, a similar view of the same with the trunk piston in its upper position, the valve ring in the abutment head being open establish-

ing communication between the compression and combustion chambers, and the exhaust valve being open for the exhaust of the burnt gases. Fig. 3, a similar view showing the trunk piston in its initial downward movement or stroke just after the ignition or explosion of the combustible charge, the valves being closed. Fig. 4, an enlarged perspective view of the valve ring in the cylindrical abutment for opening and closing communication between the combustion and compression chambers.

Similar numerals of reference designate like parts throughout all the figures of the drawings.

The improved engine comprises a power or working cylinder 1, provided with a cylindrical abutment or head 2, extending in and spaced from its side walls forming an annular combustion chamber 3, said power or working cylinder 1, in the present instance, being provided with a crank case or base 4. The crank case is provided with suitable bearings 4^a, for the reception of a suitable crank shaft 5, the latter being provided with a crank 5^a, connected to the trunk piston hereinafter described, by means of a piston rod 6.

It will be understood that any convenient and suitable number of power cylinders and trunk pistons with their appurtenances may be employed, and any suitable and convenient arrangement provided, as in automobiles, or the like.

The power and compression pistons 7 and 8 respectively, are preferably arranged integral in the form of a trunk piston shell, the latter receiving and being adapted to reciprocate over the cylindrical abutment and within the annular compression or power chamber 3, of the power or working cylinder 1. It will be observed that the trunk piston shell forms a compression, or pump chamber 9, between the abutment 2, and the compression piston 8, so that the compression chamber 9, is formed within the trunk piston shell, as shown.

As a means for conducting the fuel oil or fluid hydrocarbon (or combustible charge if a carburetor is used) the cylindrical abutment 2, is provided with a centrally located longitudinally extending bore or charge inlet port 10, communicating at one end with a suitable fluid inlet port or conduit pipe 11, and provided at its opposite end with a valve 12, the latter being adapted to open and close

with the reciprocation of the trunk piston, and being provided with a valve stem 12^a, projecting outside of the working cylinder head and provided with a suitable spring 13, and adjusting nuts 13^a.

As a means for giving the incoming fluid, or combustible charge, as the case may be, a spiral or gyratory motion, and particularly as a further means of volatilizing a volatile liquid hydrocarbon through heat transmitted through the walls of the abutment 2, the bore or inlet duct is provided with spiral grooves 10^a, it being obvious that upon the initial downward movement of the trunk piston, the valve 12 will open to permit the passage of the fuel charge into the compression or pump chamber 9 as indicated in Fig. 1, and that upon the return movement of the trunk piston, the valve 12, will be closed and the fuel charge compressed therein until transferred into the annular combustion chamber 3, as hereinafter described.

The terminating portion 2^a, of the cylindrical abutment 2, which is adapted to remain within the trunk piston at all times is of slightly larger diameter than the remaining portion of the cylindrical abutment so that an annular charge transfer space 2^b, is provided for the transfer of the combustible charges under compression from the compression chamber 9, at a proper time, by the operation of a valve in the terminating portion 2^a, of the abutment 2, to be now described.

35 As a means for opening and closing communication between the annular combustion or working chamber 3, and the compression or pump chamber 9, the abutment 2, is provided at or near its terminating portion 2^a, 40 with an annular valve groove or way 2^c, containing a valve ring 14, loosely mounted therein, said valve ring closely fitting within and against the walls of the trunk piston and being provided with a series of stop pins or studs 14^a, (see Fig. 4,) so that when in its upper or open position, as shown in Fig. 2, a passage-way will be formed over and about the same leading to the annular combustion chamber 3, through the charge transfer space 2^b, and communicating with the compression chamber 9, when the position of the trunk piston has brought the vertically extending charge transfer grooves 8^a, 45 into communication with the valve groove 2^c, as illustrated most clearly in Fig. 2, of the drawings. The terminating portion 2^a, of the cylindrical abutment 2, is provided with a ring 15, fitting within the compression chamber 9, of the trunk piston shell thus 50 serving to confine and compress the fuel charge within the compression chamber 9, until the transfer grooves 8^a, of the latter are brought past the same and into communication with the annular valve groove or way 2^c, and the valve ring 4, is elevated

whereby the charge is permitted to escape under compression into the annular combustion or working chamber 3, as above explained.

The burnt gases or products of combustion 70 are permitted to escape through an exhaust or eduction port 16, by the opening of an exhaust valve 17, as illustrated in Fig. 2, of the drawings, said valve 17, being adapted to be operated in any suitable and convenient 75 manner, as for example,—by means of a spring resisted valve stem 17^a, operated by a spring resisted rod 18, mounted in bearings 19, and riding on a suitable cam 20, on the crank shaft 5, as illustrated in Fig. 1, of 80 the drawings.

The combustible charge in the annular combustion or working chamber 3, is adapted to be ignited at suitable intervals through the medium of a suitable spark plug 21, and 85 suitable electrical connections, as for example,—in the present instance, through the medium of a contact pin or element 22, adapted to make contact with the contact spring 23, the latter being insulated from 90 and carried by a lever member 24, said lever member being adapted to be operated and left in certain predetermined positions whereby the exact time of ignition may be 95 regulated with respect to the position of the trunk piston.

From the foregoing description, taken in connection with the accompanying drawings, the operation and advantages of my invention will be readily understood. 100

Having thus described one of the embodiments of my invention, what I claim and desire to secure by Letters Patent is,—

1. In an internal combustion engine, a power cylinder provided with a valved cylindrical abutment extending therein and forming an annular combustion chamber, and a trunk piston shell forming a compression chamber in front of said cylindrical abutment and provided with charge transfer 105 members adapted to coöperate with said valved cylindrical abutment and open and close communication between said combustion and compression chambers.

2. In an internal combustion engine, a power cylinder provided with a valved cylindrical abutment extending therein and forming an annular combustion chamber, and a trunk piston shell forming a compression chamber in front of said cylindrical 110 abutment and provided with charge transfer means adapted to be brought into and out of communication with said annular combustion chamber.

3. In an internal combustion engine, a power cylinder provided with a cylindrical abutment extending therein forming an annular combustion chamber, a trunk piston shell operable in the latter and forming a compression chamber in front of said cylinder 125 130

drical abutment, and valve mechanism within said abutment adapted to open and close communication with said compression chamber during the reciprocation of said 5 trunk piston shell.

4. In an internal combustion engine, a power cylinder provided with a cylindrical abutment having an annular valve groove and a valved charge inlet port, a trunk piston shell provided at one end with charge transfer grooves adapted to be brought into and out of communication with said annular valve groove, and a valve ring spaced from the inner walls of said valve groove and 10 adapted to reciprocate therein.

5. In an internal combustion engine, a power cylinder provided with a cylindrical abutment forming an annular combustion chamber, said cylindrical abutment having a 15 longitudinally extending bore provided with spirally arranged grooves, a valve at the inner end of said bore and provided with a spring resisted adjustably mounted valve stem extending therethrough, a trunk piston shell forming a compression chamber in front of said cylindrical abutment, and a valve in the lower end of said abutment 20 adapted to open and close communication between said compression and combustion chambers.

6. In an internal combustion engine, a power cylinder provided with a cylindrical abutment and an annular combustion chamber, a trunk piston shell operable on said 25 abutment and within said annular combustion chamber and forming a compression chamber in front of said abutment, valves in the latter and adapted to be alternately opened and closed with the reciprocation 30 of said trunk piston shell whereby fuel charges are successively received, compressed, and transferred into said annular combustion chamber, and a valve ejection port communicating with the latter.

7. In an internal combustion engine, a

power cylinder provided with a cylindrical abutment having a valved inlet port and having an annular valve groove, a valve ring loosely mounted therein, and a trunk piston shell mounted in said power cylinder and 50 adapted to reciprocate over said abutment and forming a compression chamber in front of the latter, said trunk piston shell being provided with charge transfer grooves or ports adapted to be brought into and out 55 of communication with said annular valve groove.

8. In an internal combustion engine, a power cylinder provided with a cylindrical abutment, the latter being provided with an 60 enlarged terminating portion or head having an annular valve groove, a trunk piston shell fitted on and adapted to reciprocate on said enlarged terminating portion and provided with charge transfer grooves adapted 65 to be brought into and out of communication with said annular valve groove, and a valve ring loosely mounted in said annular valve groove and to reciprocate therein in coöperation with said trunk piston shell 70 and charge transfer grooves.

9. In an internal combustion engine, a power cylinder provided with a cylindrical abutment head spaced from the side walls forming an annular combustion chamber, a 75 trunk piston shell receiving said abutment head and operable in said annular combustion chamber, said trunk piston shell forming a compression chamber, means for opening and closing communication between the 80 combustion and compression chambers, and valved outlet and inlet ports communicating with the latter.

In testimony whereof I have affixed my signature in presence of two witnesses.

JOHN LOFTUS.
